BROOM, BRUSH, AND THE LIKE

Werner Kraft, New York, N. Y.

Application May 28, 1937, Serial No. 145,171

4 Claims. (Cl. 306—19)

The present invention relates to brooms, brushes and the like, and is of particular advantage with solid back brushes, such as hard brooms or scrubbing brushes.

An object of the invention is to provide a twin broom or brush the handle of which is movable relatively to the body or back member carrying the bristles, broom straws or other fibrous or wire filaments.

Another object of the invention is to provide a solid back broom or brush having a movable handle, in which the tendency to raise the trailing edges of the back members during the sweeping action is reduced, and in which means may be present for braking the relative movement of the handle and the back member.

The invention consists of two back members having a common axle and being connected to each other with a gap therebetween, and a handle journaled on said axle in said gap, said axle being located substantially below the longitudinal axis of equilibrium of said back members.

Other objects and details of the invention will be apparent from the description hereinafter of embodiments thereof, illustrated by way of example in the accompanying drawing in which:

Fig. 1 is an elevation, partly in section, of a brush according to my invention;

Fig. 2 is a section along line 2—2 of Fig. 1;

Fig. 3 is a side view, and

Fig. 4 a plan bottom view of a part of the brush;

Fig. 5 is a top plan view of another modification, and

Fig. 6 is a section along line 6—6 of Fig. 5;

Fig. 7 is an elevation, partly in section, of another modification, and

Fig. 8 is a section along line 8—8 of Fig. 7.

Referring now to Figs. 1 and 2, two solid back members 20 and 21 are provided with bristles 2 fastened thereto in any suitable manner as well-known in the art. The back members may be made of wood or of metal, and the bristles may be of animal hair, broom straw, fibrous material, or of wire. The term bristles used hereinafter and in the claims is to be understood therefore as comprising any material suitable for brooms and brushes. The members 20 and 21 are provided each with a longitudinal bore 3 and a number of vertical bores 2', the latter serving for the attachment of the roots of the bristles 2 to the back members. Bores 3 are close to the ends of the holes 2', that is to say they are arranged as low as possible and below the longitudinal axis of equilibrium 4 of the members 20

and 21. With the term axis of equilibrium I denote that axis about which the back members may swing without the tendency of taking a definite position owing to their gravity. An axle 22 is inserted into the bores 3 and held in its position by set screws 23 and 24. A handle holder 8 of metal is journaled on axle 22 in the gap between members 20 and 21. In Figs. 3 and 4, holder 8 is shown as a clamp having holes 10 through which axle 22 is passed in Fig. 1. The clamp has two projections 11 with holes 12 for a screw bolt 13 with nut 14. A handle or broom stick 15 may be inserted in the holder or clamp 8 and fastened thereto by tightening nut 14. In order to ensure the connection of the handle to the device, I provide the lower end of the handle with a groove 16 which fits over axle 22, as shown in Fig. 2. In this manner the handle may clasp the axle and swivel about it, together with the holder 8. A broom or brush according to my invention freely adjusts itself to the surface to which it is applied no matter at what angle to the surface the broom stick is directed. The arrangement of the axle below the longitudinal axis of equilibrium of the back member excludes or at least reduces an undesirable tendency of the broom to swivel relatively to the handle into a definite position, because the weight of the bristles protruding from the back member counterbalances the difference in weight of the back member portion above the axle minus the portion below the axle. In addition thereto, a braking means may be provided in order to prevent a free relative movement of back member and handle, and to permit such movement only when a certain torque is created owing to the sweeping or scrubbing force applied at the handle. Such braking means may consist of compression springs 25 and 26 acting with their ends sideways against holder 8, and back members 20 and 21 respectively so as to create a certain friction force between the parts movable relatively to each other.

Metal ties 27 and 28 are fastened to the back members by screws 29 and 30, and hold them in their desired relative position. It will be noted that these ties, when present, render the set screws 23 and 24 unnecessary in as much as axle 22 cannot be removed in axial direction. On the other hand, if the set screws 23 and 24 are used, one may do without the ties 27 and 28. Consequently, the set screws and ties may be considered as alternatives, only the ones or the others being necessarily present at the same time.

In order to make the entire length of the double

brush useful, the bristles are so flared at the inner ends of the back members as at 31 and 32 that they span the distance between these members and provide an uninterrupted brushing surface from one outer end 33 of the brush or broom to the other end 34.

Figs. 5 and 6 illustrate a modified form in which the assembling is particularly simplified.

In these figures, the back members 50 are 10 chamfered at the sides 51 and towards the outer ends at 52. This gives the back members a desirable appearance as well as sufficient material to counterbalance the bristles-provided portion in relation to their common axle 53. Each back 15 member has a bore 54 fitting the diameter of axle 53 and extending from the end opposite to the chamfered end portion towards the interior of the back member. Another and wider bore 55 extending from the end 52 coaxially with bore 54 20 meets the latter so as to form a shoulder 56 in the interior of the back member. This design is chosen, because I have found difficulties to pass a bore with the small diameter of axle 53 through the entire length of the back member. 25 Into bore 55, a tube 57 is inserted with an inner diameter corresponding to the outer diameter of axle 53. Tube 57 reaches substantially from shoulder 56 to the end 52 of back member 50. Axle 53 is provided with a head 58 at one of its 30 ends, and has a threaded portion 59 with nut 60 at its other end. Axle 54 is passed through the entire length of tubes 57, and bores 54 of the two back members 50 which are arranged at a distance to each other. In the gap 61 between both back 35 members a handle holder 8 and springs 25 and 26 are arranged on axle 53 in the same manner as shown in Fig. 2. The back members are furthermore provided each with two bores 62 parallel with bore 55. All bores mentioned in the foregoing are very close to the roots of the bristles 2 and with their axes below the axes 4 of equilibrium of the back members 50. Two pins 63 being slightly shorter than the sum of two times the length of a bore 62 plus the width of gap 61 are 40 inserted into the bores 62 of the two back members which are symmetrically arranged opposite each other on axle 53. This arrangement provides that the axle 53 may be located substantially below the axis of equilibrium of the back members. When the parts are assembled, as 45 shown, nut 60 permits to adjust the compression of springs 25 and 26, so as to give the desired amount of frictional resistance to a relative movement of the back members and handle holder 8. Pins 63 prevent relative movement of the back members in relation to each other, and, furthermore, prevent turning over of the back members, because they limit the relative movement of the 50 handle holder at a definite angle from its center position.

In some instances, however, I have found that a broom or brush as described in relation to Figs. 1 to 6 has the tendency of raising the trailing edges of the back members when their front edges 65 encounter an unevenness. In order to overcome this drawback, I prefer to arrange the axle of the back members substantially flush with the lower surface of the back members, in fact between the bores for the bristles. A preferred form is illustrated in Figs. 7 and 8.

Two back members 70 are arranged symmetrically with each other and so as to form the longitudinal continuation of each other with a gap 71 therebetween. Each back member has in its vertical center plane a longitudinal cavity or groove

72 between the holes 73 and 74 of two rows of bristles 93, and two recesses 75 and 76 in its walls 77 and 78 respectively. Each recess is formed as a segment of a circle the radius of which is longer than the distance of the circle center 79 from the 5 lower surface 80 of the back member. Circular plates 81 are fitted into the recesses 75 and 76, and are provided with an eccentric hole 82 opposite the longitudinal groove 72. An axle 83 is passed through the holes 82 of all plates 81 in the 10 recesses 75 and 76 of both back members 70 so as to be housed in their grooves 72. Axle 83 has a head 84 and a threaded end portion 85 with nut 86, and carries, in gap 71, the handle holder or clamp 8 with handle 15 so that the holder with 15 the handle may swing about the axle. Compression springs 87 and 88 are interposed between clamp 8 and the plates 81 near gap 71. Head 84 and nut 86 of axle 83 hold the parts of the device together, and nut 86 permits an adjustment of the 20 compression springs, and hence of the friction force resisting to a relative movement of the back members and the handle. Bores 89 and pins 90 may be provided in a similar manner to and for the same purpose as bores 62 with pins 63 in the 25 embodiment of Fig. 5. In order to allow for a sufficient angle of oscillation of the handle, bores 89 are also arranged as low as possible, that is to say between two rows of holes 91 and 92 for the bristles, and approximately on the same level as 30 axle 83. The bristles are so flared at 93' that they close gap 71 at the sweeping surface. The very low location of axle 83 excludes or at least considerably reduces the tendency of the back members of raising the trailing edges during the 35 sweeping action when the bristles strike an obstacle as for instance a threshold.

The construction of the embodiment according to Fig. 7 is of particular advantage, because it requires only one screw nut to be tightened in 40 order to secure all parts together. The head and the nut of the axle in cooperation with the springs hold the plates 81 in the recesses 75 and 76, and the plates hold the axle in the grooves 72, simultaneously transmitting the force applied at 45 the handle to the back members.

Various modifications may be made without departing from the nature of the invention as set forth in the appended claims.

I claim:

1. A brush comprising two bristles-provided solid back members having a common longitudinal axis of equilibrium, and each having a longitudinal cavity through at least part of its length below said axis, said back members being arranged at a distance to each other with a gap therebetween, an axle inserted into said cavities of said back members so as to bridge said gap, means for holding said back members together, a handle holder journaled on said axle within said gap between said back members, and resilient means operative in opposite directions from said holder and bearing against said back members so as to create a frictional resistance to a relative movement of said back members and said handle holder.

2. A brush comprising two bristles-provided solid back members, each having a longitudinal axis of equilibrium, said back members being arranged one as the continuation of the other one with a gap therebetween, means for holding said back members in their relative position, each back member having an elongated cavity substantially below its longitudinal axis of equilibrium, an axle inserted in said cavities and bridging said 75

gap, a clamping device for a handle journaled on said axle in said gap, and springs on said axle at both sides of said clamping device and bearing against said back members so as to create a frictional resistance to a relative movement of said back members and said clamping device.

5 3. A brush comprising two bristles-provided solid back members, said back members being arranged lengthwise and symmetrically with respect to each other and with a gap therebetween, an axle attached to the back members substantially flush with their lower surfaces so as to bridge said gap, a handle holder journaled on said axle in said gap, and resilient means operative in opposite directions from said holder and bearing against said back members so as to create

a frictional resistance to a relative movement of said back members and said handle holder.

4. A brush comprising two solid back members, said back members being arranged lengthwise and symmetrically with respect to each other and with a gap therebetween, each back member having several rows of holes for bristles to be secured therein, and a groove between two of said rows of holes, an axle secured to said back members in said grooves, a handle holder journaled on said axle in said gap, and resilient means operative in opposite directions from said handle holder and bearing against said back members so as to create a frictional resistance to a relative movement of said back members and said handle holder. 10 15
